UNITED STATES PATENT OFFICE.

GIDEON C. SPELLINGS, OF HUNTINGDON, TENNESSEE.

SIGNAL FOR RAILROAD CARS.

Application filed October 26, 1923. Serial No. 671,020.

To all whom it may concern:

Be it known that I, GIDEON C. SPELLINGS, a citizen of the United States, residing at Huntingdon, in the county of Carroll and 5 State of Tennessee, have invented a new and useful Signal for Railroad Cars, of which the following is a specification.

This invention relates to a signaling device especially designed for use on railway 10 trains or the like, the primary object of the invention being to provide means controlled by the coupling of the car to which the device is attached for actuating a bell or similar audible signal.

15 Another object of the invention is to provide a device of this character which will give a signal when cars are uncoupled, warning persons of the approach of a car when the same has been uncoupled, and released 20 from a train of cars.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without 30 departing from the spirit of the invention.

Referring to the drawings:

Figure 1 is a bottom plan view disclosing a signaling device constructed in accordance with the present invention as applied to 35 railway cars.

Figure 2 is a side elevational view.

Figure 3 is a sectional view through the signal actuating means and housing supporting the same.

40 Figure 4 is a sectional view taken at right angles to Figure 3.

Figure 5 is an elevational view disclosing one end of the operating shaft.

Referring to the drawings in detail, the 45 reference character 5 designates the usual railway car construction, to which the signaling device forming the subject matter of the present invention is supplied.

The device includes a housing indicated 50 generally by the reference character 6 which housing is formed with an opening 7 in the rear wall thereof and an opening 8 in the forward wall thereof, the opening 7 accommodating an operating shaft 9 that is arranged to operate at one side of one of the

wheels of the car, as clearly shown by Figure 1 of the drawings.

This shaft 9 is supported in the movable bearings 10 that are formed with elongated openings to accommodate the bolts 11 secured to the lower end of the bracket 12 that depends from the upper wall of the housing. Thus it will be seen that due to this construction, the shaft 9 may be moved laterally to bring the same into and out of contact 60 with the wheel of the car, associated therewith to operate the signaling device.

Connecting the bearings 10 is a bar 12' which is provided with an outstanding ear 13 to which the arm 14 is pivotally connected, 70 the arm 14 being also connected with the head 15 of the operating rod 16. A connecting link 17 also has connection with the head 16 and has its opposite end anchored to one wall of the housing 6 as 75 clearly shown by Figure 3 of the drawings.

Bearing members 18 are secured within the housing 6, and these bearing members support the rod 16 and as shown, this rod 16 is provided with a head 19 lying in the 80 path of travel of one of the coupling heads of the adjacent car, so that when the coupling heads are coupled, the rod 16 will be moved towards the housing 6 as shown by Figure 3 of the drawing, which in turn 85 moves the shaft 9 laterally and out of contact with the wheel associated therewith.

A coiled spring 20 is mounted on the rod 16 and has one end thereof abutting one of the bearing members 18, the opposite end 90 engaging the pin 21 carried by the rod 16, to normally urge the rod to the limit of its outward movement which moves the shaft 9 to its active position.

In order that movement of the rod 16 will 95 be restricted, a spring finger 22 is provided, which bears against the rod 16 to prevent rattling thereof. Formed on the inner end of the shaft 9 is a pin 23 which is eccentrically located with respect to the end of 100 the shaft 9, to engage the arm 24 of the tapper mechanism which includes a pivoted arm 25 formed with a tapper 26 at its upper end, which tapper moves within the bell 27 to make an audible signal. The arm 24 extends into an opening in the shaft 9, whereby movement of the shaft results in a relative movement of the arm 24 to sound the alarm.

From the foregoing it will be obvious 105 that when cars are coupled, the shaft 9 will 110

be thrown out of operation, but when the cars are uncoupled, the spring 20 will act to move the rod 16 in a direction opposite to the direction of the arrow as shown by 5 Figure 3 of the drawings, whereupon the shaft 9 will be moved laterally into engagement with the wheel of the car which will cause the shaft 9 to rotate. As the shaft 9 rotates, movement is imparted to the 10 arm 24 as described.

It is believed that in view of the foregoing detail description, a further detail description as to the operation of the device is unnecessary.

15 I claim:

1. In combination with the coupler heads and supporting wheels of railway rolling stock, a housing supported adjacent to the coupler heads, a signaling device within the 20 housing, a shaft extending into the housing and adapted to be moved into engagement with one of the supporting wheels to operate the signaling device, and means in the path of travel of the coupling heads and 25 adapted to be moved by its engagement with the coupling heads for moving the shaft into and out of engagement with the wheel for controlling the sounding of the alarm.

2. In combination with the coupler heads and supporting wheels of railway rolling stock, a housing supported adjacent to the coupler heads, a signaling device in the 30 housing, and including a pivoted arm, movable bearings within the housing, a rotatable shaft supported in the bearings, said shaft adapted to be moved to frictionally engage the supporting wheel associated therewith, a 35 slideable rod adapted to move in the housing, and means for connecting the rod with the bearings to cause the shaft to move laterally in the housing and into engagement with the wheel for controlling the sounding of the alarm.

3. In combination with the coupler heads and supporting wheels of railway rolling stock, a signaling device including a housing, supported adjacent to the coupler heads, movable bearings within the 40 housing, a rotatable shaft supported in the bearings and adapted to move to frictionally engage the supporting wheel associated therewith, a signaling member within the housing and adapted to be operated by the rotation of the shaft, and means in the 45 housing and adapted to contact with a coupler head for moving the shaft into and out of engagement with the wheel for controlling the sounding of the alarm.

4. In combination with the coupler heads and supporting wheels of railway rolling stock, a signaling device including a housing, a laterally 50 movable shaft within the

housing and adapted to move into frictional engagement with one of the supporting wheels to rotate the shaft, a signaling member within the housing and adapted to be operated by the rotation of the shaft, and means for automatically throwing the shaft into and out of contact with the supporting wheel associated therewith for controlling the sounding of the alarm.

5. In combination with the coupler heads and supporting wheels of railway rolling stock, a signaling device including a housing, a shaft positioned within the housing, a signaling member within the housing, a movable shaft extending into the housing and adapted to be rotated by frictional engagement with one of the wheels, means for transmitting movement of the shaft to the signaling member, and means for moving the shaft into and out of contact with the wheel associated therewith for controlling the sounding of the signaling member.

6. In combination with the coupler heads and supporting wheels of railway rolling stock, a signaling device including a housing, a shaft extending into the housing and adapted to move laterally therein, said shaft adapted to frictionally engage one of the supporting wheels to receive motion therefrom, a signaling member within the housing, and operated by the rotary movement of the shaft, and an operating rod adapted to move the shaft into and out of contact with the supporting wheel associated therewith for controlling the sounding of the alarm.

7. In combination with the coupler heads and supporting wheels of railway rolling stock, a signaling device including a housing, supported adjacent to the coupler heads, a signaling member within the housing, a rotatable shaft extending into the 100 housing and adapted to be rotated by frictional engagement with one of the supporting wheels, an operating rod adapted to slide into the housing, said operating rod adapted to engage the coupler head to move the rod in one direction, means for connecting the rod to the shaft to cause the shaft to move laterally into engagement with the supporting wheel to cause the sounding of the signaling device and means 105 for returning the rod to its normal position.

In testimony that I claim the foregoing as my own, I have hereto affixed my signature in the presence of two witnesses.

GIDEON C. SPELLINGS.
